US00D457244S

(12) **United States Design Patent**
Loutis et al.

(10) Patent No.: **US D457,244 S**
(45) Date of Patent: **** May 14, 2002**

(54) **BIOMEDICAL ELECTRODE PORTION**

(75) Inventors: **Nicolaus Loutis, Borken; Paul Weidenhaupt, Gummersbach, both of (DE)**

(73) Assignee: **3M Innovative Properties Company, St. Paul, MN (US)**

(**) Term: **14 Years**

(21) Appl. No.: **29/119,688**

(22) Filed: **Mar. 6, 2000**

(30) **Foreign Application Priority Data**

Sep. 10, 1999 (GB) 2086582

(57) **CLAIM**

The ornamental design for a biomedical electrode portion, as shown and described.

DESCRIPTION

FIG. 1 is a perspective view of the biomedical electrode portion showing our new design;

FIG. 2 is a top view thereof;

FIG. 3 is a bottom view thereof;

FIG. 4 is a front view thereof;

FIG. 5 is a rear view thereof; and,

FIG. 6 is a side view thereof.

The broken lines in the figures show a part of the biomedical electrode for illustrative purposes only and form no part of the illustrated design.
